Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed December 9, 1921. Serial No. 521,089.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

The present invention relates to means 10 for holding cards or labels on the platen of a typewriting machine to permit of inscriptions being printed thereon. More particularly, the invention relates to a holder for this purpose, mounted sufficiently far 15 toward one or the other end of the platen as to permit of a work-sheet being positioned on the platen alongside of the card or label in the holder.

In certain uses of a typewriting machine, 20 it is desirable to print inscriptions upon a card or label in conjunction with the printing of matter on a work-sheet to which the matter inscribed upon the label has some relation. For example, a typewriting ma- 25 chine operator for a telephone company may be engaged in writing subscribers' requisitions either upon separate work-sheets, or upon individual forms detachable one after another from a continuous web.

At the same time that the requisition-sheets 30 or form-blanks are filled in, it is desirable to have the subscribers' telephone-numbers written upon the tabs or cards which are to be attached to the mouth-pieces of the 35 telephone-instruments. In order that such tabs, cards or labels may have the telephone-numbers inscribed thereon, concurrently with the writing of the requisition-sheets, and more especially where the requisition- 40 sheets comprise detachable blanks forming a continuous web which it is inconvenient to remove, it is desirable to have the card or label holder so mounted that the cards or labels may be inserted into and removed 45 from the same without disturbing the web or work-sheet at the side thereof.

Card or label holders variously mounted 50 on either the main frame, carriage or platen are old in the art. Such holders, when not on the platen, have heretofore required a feed of the card or label, leading-end first, around the platen in line-space direction from the rear thereof, or, if permitting insertion of the card or label from the front

of the machine, have ordinarily called for 55 an insertion of the card or label, bottom-end first, and a subsequent feed of the card or label to printing position; in the use of both of which general forms of card or label-holding devices certain auxiliary guiding 60 and feeding mechanisms and parts are required; or, no provision is made for use in conjunction therewith of means for holding and feeding on the platen work-sheets or webs related to the cards or labels. When 65 directly mounted on the platen, the holder has heretofore not ordinarily been susceptible of use in conjunction with the type- 70 writing of sheets or webs requiring a complete revolution of the platen.

An object of the invention is the provi- 75 sion of a card or label holder such that the cards or labels may be inserted therein, leading-end first, from the front of the machine. Another object of the invention is the provision of a card or label holder such that, without turning the platen, or dis- 80 turbing the position of any work-sheet or web thereon, the card or label may be in- 85 serted from the front of the machine and brought to correct printing position in the holder.

A feature of the invention is the provision 90 of a card or label holder, for use in the platen in conjunction with means for holding a work-sheet or web on the platen along- 95 side the card or label, and so designed and mounted that, by shifting the carriage, the card or label holder may be made to clear the main frame of the machine, to permit 100 the cards or labels to be inserted into the machine, and directly into the holder, lead- 105 ing-end first, from the front of the machine.

Another feature of the invention is the provision of a card or label holder mounted 95 on the carriage, and such that, without a feeding movement of the holder, or a feed of the card or label by turning the platen, the card or label may be positioned at the 100 printing line in the holder.

Another feature of the invention is the combination in a continuous billing type- 105 writing machine of means for feeding a continuous work-web to the machine, a platen mounted for displacing movement to permit straightening of the web, a card- holder for holding a card in writing position beside the web, and gearing arranged

to turn the platen as an incident of its dis- placing movement to eject the card from its holder.

Other features and advantages will here- 5 inafter appear.

In the accompanying drawings,

Figure 1 is a front view of the platen carriage, platen, and certain associated parts, of a front-strike machine, with the label holder 10 on the carriage and a label and associated work-sheet or web on the platen.

Figure 2 is a view in cross-sectional side elevation on the line 2—2 of Figure 1.

Figure 3 is a perspective view, showing 15 the mounting of the label holder on the paper-table of the carriage, and the manner in which it holds the label to the platen.

In the drawings, the invention is shown as applied to a fan-fold machine. In this ma- 20 chine, the fan-folded web 10 passes over a carbon-carriage (not shown) which travels on a table 11; and from the carriage the web is fed over a paper-shelf 12 at the rear of the table, and thence downward around the 25 platen 13, finally to be brought up over a shelf or table 14 at the front of the platen, where the successively typewritten sections of the web are detached by drawing the web against a knife 15 at the front of the ma- 30 machine.

In fan-fold machines, the platen common- 35 ly is liftable from a normal, Figure 2, position, to a position (not shown) in which suc- cessive blanks of the web are brought for- 40 ward to printing position. For this purpose, the frame 16, in which the axle 17 of the platen is mounted, is itself pivoted on a rod 18, mounted in the frame 19 on the carriage 20. Hooks 21, fast to a rod 22 pivotally 45 mounted on the frame 19, are engageable with pins 23 on the side-pieces of the pivot- 50 ally-mounted frame 16, to hold the latter, with the platen, in the normal, Figure 2, position. A suitable hand-device (not shown) 55 releases the hooks 21 from the pins 23 to permit of pivotal movement of the frame 16; and a spring (not shown) causes the hooks 21 automatically to engage and hold the pins 23 when the platen is returned to normal po- 60 sition.

On the cross-piece 24 of the carriage, at the rear of the platen, is secured a bar 25; and the shelf 12 at the rear of the platen is secured to this cross-bar 25. It will be noted, 55 in Figure 2, that, except for certain tongues 27 on the rear edge of the shelf 12, the shelf 12 is offset upward at 28 and then hori- 60 zontally rearward over the rod 22, on which the hooks 21 are mounted.

The table or shelf 14 at the front and above the platen is secured by screws 29 to a cross-bar 30, connecting the side-pieces of the pivotal frame 16.

For effecting line-space movement of the 65 platen, there is fast to the axle 17 of the

platen a pinion 31, in mesh with a pinion 32 revoluble on the rod 18 on which the platen-frame 16 swings; so that the pinion 31 is in mesh with the pinion 32 in all positions of the platen. Revolvably mounted in fixed po- 70 sition on the carriage 20 is a line-space shaft 33, fast to which is a pinion 34, also permanently in mesh with the pinion 32 on the shaft 18. A line-space ratchet-wheel 35, op- erable in any well-known way by a pawl and 75 line-space lever, is fast to the line-space shaft 33. Line-space movement of the platen is therefore effected from the ratchet 35, through shaft 33, pinion 34, to pinion 32, to pinion 31, and to the platen-axle 17, in all 80 positions of the platen.

In order that the platen may be given a line-space movement by either hand, there are, at the right-hand side of the carriage, a shaft 33 and pinions 31, 32 and 34, simi- 85 lar to, and having connections similar to, the shaft 33 and pinions 31, 32 and 34 at the left-hand end of the carriage. Hand-wheels 33^a are shown on the shafts 33. The usual front and rear feed-rolls 37, 38 are indicated 90 in dotted lines in Figures 1 and 2; and the printing point is indicated in Figure 1 by the type-guide 39, type 40 and type-bar 41. Thus far, the parts described are those 95 found in the Underwood fan-fold typewrit- ing machine.

The card or label holder of the present invention is shown at the right-hand of the table 14 in Figure 1. Secured, as by means of one of the screws 29, to the table 14 is a 100 strip of metal 45, which (see Figure 2) pro- trudes beyond the lower forward edge of the table 14. Riveted at 46 to the strip 45 is a spring U-shaped piece of sheet-metal 47 hav- 105 ing two fingers 48 curved, in conformity to the circumference of the platen, down and around the front of the platen, and slightly upturned at 49 at their distal ends. The spring-action of the fingers 48 causes the same to bear against the platen, so that any 110 card or label 50 inserted between the same and the platen will be held in place against the latter. The fingers 48 are spaced apart sufficiently to permit printing, such, for instance, as the printing of a telephone num- 115 ber, to be effected between the same. In Figure 3, the printing of the telephone number "4001" is shown as having been made un- 120 der the name of the telephone exchange "Spring". The side edges of the fingers 48 may be used to align the edges of the card or label 50.

As shown in the drawings, the writing on the cards or labels 50 is effected in connec- 125 tion with the writing of the individual forms on the web 10. For instance, each individual form, as written, may represent the requisition of a subscriber for telephone service; and the number assigned to that subscriber is written on the card or tab 50, 130

which is subsequently affixed to the telephone mouth-piece. It will be noted (see Figure 1) that the web 10 is sufficiently narrow to permit of space to the right thereof 5 on the platen for the card 50.

In positioning the card or label, the platen carriage is drawn to the right, so that card holder 47 lies to the right of the right-hand side 52 of the machine frame. The card is 10 then slipped from the right, underneath the carriage frame, and up under the fingers or clips 48 of the card holder 47, the upturned ends 49 of the clips guiding the card upward.

15 When the work-sheet and label have been completed, the platen is displaced to permit straightening of the work-web preparatory to the usual carbon-withdrawing, web-gaging and tearing-off operations. The 20 pinions 31 and 32 are operatively engaged with each other throughout the displacing movement, the latter pinion remaining stationary. This causes the pinion 31, and consequently the platen, to be rotated in an 25 anti-line-feed direction to automatically eject the card from its holder, at the lower end thereof, during the displacing movement.

Variations may be resorted to within the 30 scope of the invention, and portions of the improvements may be used without others.

Having thus described my invention, I claim:

1. In a front-strike typewriting machine, 35 a revoluble platen, a platen-frame, and a one-piece card-holder consisting of a U-shaped member curved to conform to the periphery of said platen and being self-acting to hold a card firmly against the 40 front face of said platen, said member being inverted and extending below the printing line on said platen and being secured to said platen-frame at one end thereof, to be wholly 45 outside of the bounds of the typewriter frame when the platen is in a position corresponding to its limit of travel, to eliminate 50 interference to movement accompanying an upward thrust of the card to printing position from a point below the printing line on said platen.

2. In a typewriting machine, a revoluble platen, a platen-frame having a rear paper-shelf at the delivery side of the platen, and a card-holder consisting of a U-shaped member inverted and connected at its closed end 55 to the paper-shelf to be suspended therefrom, said member being curved to conform to the periphery of said platen, also self-acting, to hold a card firmly against the 60 front face of said platen, and yielding of

itself to permit insertion of the card between it and said platen, said curvature of said member extending below the printing line on said platen at which point insertion of the card is effected, followed by an upward thrust of the card to printing position on said platen. 65

3. In a typewriting machine, a revoluble platen, a platen-frame having a rear paper-shelf at the delivery side of said platen, a screw to attach said paper-shelf to said platen-frame, and a one-piece U-shaped card-holder inverted and connected at its closed end to said paper-shelf by said screw, said card-holder curving around said platen, to hold a card firmly against the front face of said platen at the printing line and above and below said line. 75

4. In a typewriting machine, a revoluble platen, a platen-frame having a rear paper-shelf at the delivery side of said platen, a screw to attach said paper-shelf to said platen-frame, a one-piece U-shaped card-holder having a curve to conform to said platen, said card-holder being inverted and depending from said shelf to act of itself to hold a card firmly against the front face of said platen at the printing line and above and below said printing line, and being flared outwardly at the lower ends to facilitate 80 placement of the card on the printing line by an upward thrust, and a metal strip connected to said holder at its closed end, extending upwardly therefrom and being attached to said paper-shelf by said screw, 85 to support said card-holder in said depending position. 90

5. In a typewriting machine, a revoluble platen, a platen-frame having a rear paper-shelf at the delivery side of said platen, means to attach said paper-shelf to said platen-frame, a one-piece U-shaped card-holder having a curve to conform to the curvature of said platen, said holder being inverted and depending from said paper-shelf at the right-hand side thereof, across the front face of said platen and acting of itself to hold a card firmly against said platen at the printing line and above and below said line, and being flared outwardly 100 at its lower end to facilitate placement of the card to printing position by the upward thrust of the card, and an arm extending upwardly from the closed end of the card-holder and being attached to said paper-shelf. 105 110 115

JESSE A. B. SMITH.
